[57] ABSTRACT

An amusement device having a preferably transparent housing including an upright chute, and a gear train in the housing including a gear which partially extends into the chute. Plural playing pieces are associated with the device and are of a size and shape to loosely fit within, and slide down, the chute. The playing pieces have a preferably serrated periphery forming a rack for engagement with the toothed periphery of the gear which extends into the chute to initiate movement of the gear train as the playing pieces move through the chute. The bottom of the housing includes a pivoted member which extends partially into the chute for engagement by a descending playing piece and a missile element is associated therewith to the interior of the housing, remote from the chute, so as to be flipped upwardly by a descending playing piece which strikes the pivot element.

AMUSEMENT DEVICE

BACKGROUND OF THE INVENTION

1. Field of the Invention

This invention relates to amusement devices.

2. Brief Description of the Prior Art

There are many well known children's toys or amusement devices which utilize the principle of a peg or block or playing piece which traverses through a chute. One such variation includes those devices which are a hammer and bench arrangement wherein the pieces are deposited outwardly from the chute following their being driven through their openings in the bench. Generally, such devices merely utilize the principle of the block or playing piece ultimately being fed outwardly from the terminal end of the chute after initial deposit through an input end thereof with little other related mechanical motion resultant from the playing pieces or blocks traversing through the chute.

Children are typically fascinated by toys which involve motion as well as sound reproduction, particularly if the activity of the child in association with the toy helps create the motion or reproduction of sound. The younger the child, the more difficult it is for the child to be able to operate or understand the operation of toys which may require some sort of actuation by the child in order to produce movement, sound and the like. However, even children of extremely tender years are capable of understanding the concept of dropping playing pieces into a chute and watching the dispensation of the playing pieces outwardly of the chute. Since this is an easily understood and popular form of activity with extremely young children, it is the purpose of this invention to meet a need and desire in the art to utilize the concept of dropping playing pieces through a chute to initiate movements of other elements of a motion transmitting and sound reproducing toy.

SUMMARY OF THE INVENTION

This invention is directed, in brief, to an improved amusement device having internally actuated elements which are motivated by dropping playing pieces down a chute-like portion of the device.

The best mode currently contemplated for carrying out the invention includes a housing having a substantially uprightly oriented chute and a gear train in the interior of the housing including one gear member which partially intersects the chute. Playing pieces are provided having a serrated periphery forming a rack in cooperation with the gear which extends into the chute for initiating movement of the gear train as the playing pieces are dropped into the chute and engage the gear in the chute.

A pivoted member is also provided, having a portion extending into the path of travel of the playing piece below the gear which intersects the chute, so as to be struck by a descending playing piece imparting a flipping movement to the pivoted member. A lightweight missile element is associated with the pivoted member and may be flipped upwardly about the interior of the housing. A bell is mounted in the interior of the housing to be engaged by the flipped missile element and create a sound thereby.

BRIEF DESCRIPTION OF THE DRAWINGS

FIG. 1 is a perspective view of the amusement device of this invention;

5 FIG. 2 is an elevational view of the amusement device shown in FIG. 1;

FIG. 3 is a section view taken generally along the lines 3—3 of FIG. 2; and

10 FIG. 4 is a section view taken generally along the lines 4—4 of FIG. 3.

15 While this invention is susceptible of embodiment in many different forms, there is shown in the drawings and will herein be described in detail a specific embodiment in many different forms, there is shown in the drawings and will herein be described in detail a specific embodiment therefor, with the understanding that the present disclosure is to be considered as an exemplification of the principles of the invention and is not intended to limit the invention to the embodiment 20 illustrated.

BRIEF DESCRIPTION OF THE PREFERRED EMBODIMENT

25 The amusement device 10 of this invention includes a housing, generally indicated 12, having a bottom 14, a top 16 and opposite end walls 18 and 20 with end wall 18 and top 16 being joined by curved intermediate section 21. In addition, the housing includes side panels 22 30 and 24 to complete the substantial enclosure of the housing. A handle 26 extends above top 16 to facilitate the carrying about of the device 10 of this invention.

35 Adjacent the top of end wall 20 there is provided an upper playing piece opening 28, and adjacent the bottom of the end wall 20 there is provided a lower playing piece opening 30. An upright rib 32 is spaced a short distance inwardly from end wall 20 and has interruption 32a therein and terminates in an inwardly directed lower leg 32b. The open upper and lower ends 28 and 40 30 and the rib 32 combine with the end wall 20 to define therewith a playing piece path of travel, or chute 34.

45 A first movable member or gear 38, having a toothed periphery 40, extends partly through the interruption 32a in rib 32 a slight distance into the chute 34. A hub opening 42 of gear 38 is impaled upon a stub 44 that extends inwardly from side wall 24 to rotatably mount the gear 38 to the interior of the housing. The gear 38 50 includes an enlarged disc portion 46 having a plurality of outwardly projecting pins or pegs 48. The disc portion 46 and related outwardly projecting pins reside within a circular cavity 50 which is part of the structure of the side wall 22. A generally cylindrical caged element 52 of a diameter slightly smaller than the distance between pins 48 is held within the cage, resultant from the cooperation of disc 46, pins 48 and cavity 50, and is freely movable within the confines thereof.

55 Gear 38 is in meshing engagement with a gear 54 having a toothed periphery 56. Gear 56 has an opening 58 in the hub thereof which is impaled by stub 60 to also rotatably mount the gear 54 to the side wall 24 of the housing 12.

60 Gear 54 is, in turn, in meshing engagement with a gear 62 having a toothed periphery 64. Gear 62 has a hub opening 62a which is also impaled on a stub 62b of the side wall 24 to rotatably mount the gear 62 with

respect to the housing 12. In addition, the gear 62 further includes a ratchet disc portion 66 having a ratchet tooth-like periphery 68. Disc portion 66 is fixed for rotation of gear 54 and gear 38.

A pawl member 70, herein shown in the form of a simulated cow, is provided adjacent the ratchet disc periphery and includes simulated feet 72a, 72b, 72c and 72d which constitute pawl elements for engagement with the periphery 68. The pawl member 70 is pivoted at 74 to hub 76 on housing wall 24 to provide a back and forth rocker-type action to the pawl 70, so as to afford a step-by-step intermittent movement to the ratchet disc 66 responsive to the rotation imparted thereto by the other gears 38, 54 and 62 of the gear train. In addition to the intermittent movement there will be a resultant step-by-step audible sound, similar to a clicking noise.

The interior of the housing includes a second movable member, or missile flipping structure, or arm 80 having an inner end 80a and an outer end 80b. Outer end 80b is positioned within the chute adjacent the out-feed end 30 and below the leg 32b or rib 32. The arm 80 is pivoted to wall 24 at 82 off-center with respect to its length, so as to normally orient the inner end 80a downwardly and the outer end 80b upwardly with respect to the pivot 82. A missile element or ball 84 is associated with the arm 80, and preferably is a small lightweight ball similar in structure and weight to the well known ping-pong ball. A depending guide or ramp element 86 extends from base 14, upwardly at a relatively steep angle to a merger with the interior of the side wall 18 below the juncture 21 between side wall 18 and top 16. A plurality of ball deflecting pins 88a, 88b, 88c, 88d, 88e, 88f and 88g, project inwardly from the side wall 22 of the housing. These pins serve to deflect and interrupt the descending path of travel of the ball 84 as it is flipped upwardly along ramp 86, side wall 18 and intermediate portion 21, responsive to rapid pivotal movement of arm 80 about its mounting 82 as will be explained.

The amusement device further includes an audible signal producing means 90, herein shown in the form of a conventional bell. The signal producing means 90 is connected to the side wall 22 by a screw 92 and sound openings 94 are provided in wall 22 about bell 90.

The device of this invention further includes a plurality of playing pieces 96, which are preferably cylindrical in configuration, either being circular cylindrical or square cylindrical as shown in FIG. 1. Each of the playing pieces is provided with a serrated or pleated periphery 98 providing a plurality of vertically tandem oriented continuous notches affording movable member engaging surfaces, or a toothed periphery of crests 100 and roots 102, so that the playing pieces 96 constitute simulated rack members for engagement with the toothed periphery 40 of gear 38.

In operation, a user drops a playing piece 96 down the open end 28 of chute 34, and as it descends to the area of the gear 38, the serrated or pleated periphery 98 of the playing piece 96 will engage the toothed periphery 40 of the gear 38 to initiate movement of the gear and the related components of the gear train including gears 54 and 62 and ratchet disc 66. During this movement, the element 52 will be tossed about within the confines afforded by the cavity 50 and disc 46 and

the pawl 70 will intermittently engage the ratchet periphery 68 of ratchet disc 66 to provide step-by-step intermittent movement and associated intermittent clicking sound and the like.

As the playing piece 96 descends past the area of the gear 38, wherein it is temporarily slowed during this period of engagement therewith, it will then strike the outer end 80b of arm 80 causing the ball 84 to be flipped upwardly about the interior of the housing. The ball will then descend rather slowly as it is deflected between the several pins 88a, b, etc. In most instances, during its descent, the ball 84 will strike the bell 90 producing an audible signal and will ultimately come back to rest on top the inner end 80a or arm 80 inasmuch as this is the lowest portion defined by the area bounded by the ramp 86, rib 32 and walls 18 and 16 arm and curved portion 21. The operation may be repeated through the use of several such playing pieces 96 and, if the participant is quick enough, the action may be performed in a continuous nature. To enhance the amusement and entertainment value of the toy of this invention, at least the side wall 22 is preferably transparent or translucent and the remainder of the housing may be transparent as well if desired. Thus, a participant is provided with the interest afforded not only by the noise resultant from the interaction of the several elements, but also from viewing the motion resultant from the act of dispensing a playing piece down the chute.

The foregoing detailed description has been given for clearness of understanding only, and no unnecessary limitations should be understood therefrom, as some modifications may be obvious to those skilled in the art.

We claim:

1. An amusement device comprising: means defining a housing; means through said housing defining a playing piece path of travel having an input end and an output end; a playing piece of a size and shape to pass through said playing piece path of travel; said playing piece having a movable member engaging surface thereon; a first movable member movably mounted in said housing with a portion thereof intersecting said playing piece path of travel intermediate the ends of said path, and having a playing piece engaging surface thereon for cooperative engagement with said playing piece movable member engaging surface to initiate movement of the movable member engaging surface to initiate movement of the movable member responsive to travel of said playing piece through said path of travel, said first movable member being part of a movable train of interrelated members to which motion is imparted responsive to movement of said first movable member.

2. The amusement device of claim 1 wherein the movable member and playing piece have cooperative gear tooth peripheries.

3. The amusement device of claim 2 wherein the movable member includes a gear having a toothed periphery and wherein the playing piece has a serrated exterior portion defining a rack thereby for cooperative engagement with the periphery of the gear.

4. An amusement device comprising: means defining a housing; means in said housing defining a playing piece path of travel; a playing piece of a size and shape to be received in said playing piece path of travel; said

playing piece having a movable member engaging surface thereon; a first movable member movably mounted in said housing and having a playing piece engaging surface thereon for cooperative engagement with said playing piece movable member engaging surface to initiate movement of the movable member responsive to travel of said playing piece through said path of travel; and a second movable member pivoted to the housing and having a portion extending into the playing piece path of travel and a missile element associated therewith for launching into a path of travel when said second member is engaged by a playing piece moving through said playing piece path of travel.

5. The amusement device of claim 4 wherein the playing piece has a serrated exterior portion defining a rack surface thereby and wherein the movable member includes a gear having a toothed periphery for engagement with the playing piece rack surface, with the gear being part of a gear train mounted to the interior of the housing.

6. The amusement device of claim 4 including audible signal producing means in the interior of the hous-

ing in a position to be struck by the missile element following movement of said movable member.

7. The amusement device of claim 5 wherein one gear of said gear train is associated with an escapement mechanism for step-by-step movement responsive to rotatable movement of the actuated gear train.

8. The amusement device of claim 5 wherein one member of the gear train includes a cage having a loosely confined cage element therein, the cage being associated with the gear train for movement of the cage and its associated element responsive to actuation of the gear train.

9. The amusement device of claim 4 wherein the playing piece path of travel comprises a generally uprightly oriented chute having an input end and an output end with the movable member being located between said input and output ends.

10. The amusement device of claim 9 wherein said second movable member is located between said first movable member and said output end.
